United States Patent Office.

JOHN W. PIERCE, OF MILLBURY, MASSACHUSETTS.

Letters Patent No. 75,573, dated March 17, 1868.

IMPROVEMENT IN MOWING-MACHINES.

The Schedule referred to in these Letters Patent and making part of the same.

TO ALL WHOM IT MAY CONCERN:

Be it known that I, JOHN W. PIERCE, of Millbury, in the county of Worcester, and State of Massachusetts, have invented a new and improved Mode of Operating the Finger-Bar of Mowing-Machines; and I do hereby declare that the following is a full, clear, and exact description thereof, which will enable others skilled in the art to make and use the same, reference being had to the accompanying drawing, forming part of this specification, and in which—

Figure 1 is a perspective view of a mowing-machine with my improvement attached, and

Figure 2 a transverse section of the same.

Similar letters of reference indicate like parts in the two figures.

This invention is especially adapted to that class of mowing-machines which have the cutter-bar attached to the hanger-iron by a flexible joint or hinge, and consists in a very simple and efficient arrangement of two levers, a connecting-link, and guide-post, which will be hereinafter described.

The lower lever is attached by one end to the bar or shoe, in any manner whereby sufficient purchase can be obtained to raise the further end of the cutter or finger-bar by pressing upon the upper or free end of the lower lever, as will be hereinafter described. To the free end of the lower lever is attached a link, which passes through the foot-board, and is connected to the upper lever, as shown in the accompanying drawings. The upper lever is fastened to the foot-board, at one end, by hinge-joint; the other end is free to move up and down in guide-posts, as will be seen by reference to the accompanying drawings. Thus, the driver can, with his foot upon the free end of the upper lever, raise the bar above, and drop it below the plane in which the wheel or wheels of the machine are moving, and, by means of the rack on the guide-post, the upper lever may be held at any desired point.

By this arrangement, the machine will do as good work on top a ridge as on level ground, and the outer end of the bar can be raised to pass obstructions in the swath without raising the heel or inner end of the bar.

To enable those skilled in the art to fully understand my invention, I will proceed to describe its construction and operation.

A A are the driving-wheels of the machine. B is the axle; C C, the frame; D, the pole, to which is fastened the foot-board and driver's seat, the rear end of D being fastened to the axle B in any manner that may be suited to the kind of machine to which this improvement may be applied. E is the foot-board; F, the seat. G is the lever for raising and lowering the tilting-frame C C. H is the chain by which the lever and frame C C are connected at h' . I is the hanger-iron, and is firmly bolted to the frame C. J is the inside shoe, to which is bolted the finger or cutter-bar K. The shoe is hinged to the hanger-iron at i' . L is the crooked lever, passing from the shoe J to the under side of the foot-board E, as seen in fig. 2, and is shown by red dotted lines in fig. 1. It may be attached to the shoe J, as shown in the drawings, or to the joint or hinge i' , but, in practice, I prefer to put it in the hinge i' , when the shoe comes inside the hinge enough to give a good fulcrum. The lever L should be bent sufficiently to come as near the foot-board as possible, and yet not touch it at any time. By thus shaping it, it will always clear all obstructions, over which the axle will pass free. M is the link which connects the lever L to the lever N at the points 4 and 5, fig. 2. N is attached to foot-board E at and by a hinge; the other end is free to play up and down in guide-posts O. 2 2 2 are rack-teeth, for the purpose of holding the lever N in any desired position. The free end of lever N should project far enough from the post O to give ample room for the foot of the driver to operate said lever, and thereby raise and lower the outer end of the cutter-finger bar K, as shown by the red lines in fig. 2.

From this description it will be seen the object of this invention is to so arrange the several parts that they shall all be above any obstructions that will clear the axle. Secondly, that lever on upper side of foot-board can be operated with left foot, leaving right foot and both hands free for other duties, thus bringing the position of the cutter or finger-bar under perfect control of the driver, by a very simple and durable arrangement, and without in any way interfering with the other parts of the machine, as it can be applied to many machines by any one competent to operate the machine in their present state.

I am aware that many devices have been applied to mowing-machines for the purpose of raising the cutter-bars; therefore I do not wish to claim broadly the use of a lever or levers for the purpose specified.

What I claim as new, and desire to secure by Letters Patent, is—

The pivoted bent lever L, finger-bar K, rod M, lever N, and irons I, in combination with the lever G, all operating as described, whereby the inner end of the finger-bar is raised by the lever G, and its outer end by the lever L, the whole constructed and arranged in the manner and for the purpose set forth.

JOHN W. PIERCE.
